UNITED STATES PATENT OFFICE.

GEORGE B. AUSTIN, OF ATTLEBORO, MASSACHUSETTS, ASSIGNOR TO AUSTIN AND STONE, INC., OF ATTLEBORO, MASSACHUSETTS, A CORPORATION OF RHODE ISLAND.

DESIGN FOR A WATCH-BRACELET OR SIMILAR ARTICLE.

46,040.

Specification for Design.

Patented July 7, 1914.

Application filed April 9, 1914. Serial No. 830,814. Term of patent 7 years.

To all whom it may concern:

Be it known that I, GEORGE B. AUSTIN, a citizen of the United States, residing at Attleboro, in the county of Bristol and State of Massachusetts, have invented a new, original, and ornamental Design for Watch-Bracelets or Similar Articles, of which the following is a specification, reference being had to the accompanying drawings.

I claim—

The ornamental design for a watch bracelet or similar article, as shown.

GEORGE B. AUSTIN.

Witnesses:

ADA E. HAGERTY,
J. A. MILLER.
